NECKTIE PRESSING FORM

Filed June 5, 1930

UNITED STATES PATENT OFFICE

SAMUEL LOUIS GARFINKEL, OF WICHITA, KANSAS

NECKTIE PRESSING FORM

Application filed June 5, 1930. Serial No. 459,283.

This invention relates to a pressing form in the nature of an insert constructed for use and association with neckties, and adapted to maintain the aprons of the tie 5 in shape while pressing on a steam press or with a hand operating iron.

The device is especially, but not necessarily, adapted for use in cleaning and pressing establishments and is in the nature of 10 an open substantially V-shaped frame whose apex end is insertible into the tubular apron of the necktie in such a manner as to hold the aprons separately in shape while steaming and pressing, whereby to permit removing 15 of wrinkles and proper re-shaping of the necktie to render it neat and tidy for personal wear.

In carrying the inventive conception into 20 actual practice, I have developed a novel structural arrangement in the form of an open V-shaped frame composed of mechanically related companion sections of such construction and design as to render the complete device simple, economical, and 25 otherwise susceptible of fulfilling the requirements of an appliance of this classification.

In the drawings:

Figure 1 is a plan view of the form as 30 constructed in accordance with my idea and showing it in position in a necktie apron.

Figure 2 is a longitudinal sectional view on the line 2—2 of Figure 1.

Figure 3 is a cross section on the line 3—3 35 of Figure 1.

As before implied, the V-shaped frame is made up of a pair of companion side members or frame sections 4 and 5 respectively. Each member is of channel-shaped cross 40 section and fitted in the intermediate portion thereof is the elongated reinforcing and filler block 6. The blocks 6 are of a length less than the members 4 and 5. In fact, the end portions of these blocks are 45 bevelled and formed with keeper notches as at 7 to serve a purpose to be hereinafter described.

The end portions of these members 4 and 5 are provided with complementary ears 4a 50 and 5a respectively which are disposed to

gether in interfitting telescoping relationship and pivotally connected together through the medium of a pin and slot slip joint connection generally represented by the numeral 8. Both end constructions are 55 the same and the same reference characters are employed to designate the corresponding parts.

Fitted in the channel end portion of these parts 4 and 5 are arcuate springs 9 and 10 respectively whose free end portions are engaged in the keeper notches 7 and whose crown portions bear against the pin forming a part of the slip joint connection 8. These springs are for automatically expanding 65 the sections 4 and 5 of the complete frame to fit the apron 11 of the necktie.

Thus, the device is self-accommodating and fits nicely and snugly within the necktie as shown for example in dotted lines in 70 Figure 1. It might be added that the depressed ears 5a are of such a formation as shown in Figure 2 as to permit the crown portions of the adjacent springs to nest therein to aid in maintaining the springs in 75 effective expanding relationship.

It is to be added that the extended end portions 12 of the sections 4 and 5 are spaced apart to accommodate the shank portion 13 of the wooden handles or handgrips 80 14 which serve so conveniently in facilitating the insertion and removal of the complete device.

It is thought that persons skilled in the art to which the invention relates will be 85 able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in 90 actual practice if desired.

I claim:

1. In a necktie pressing form of the class described, a substantially V-shaped open frame comprising a pair of companion sections of longitudinally elongated formation provided at their opposite ends with in 100

turned telescopically connected end portions, said end portions being connected together through the medium of pin and slot joints, expansion springs located in the end portions of said sections to render the sections automatically expansible and contractable, and handles carried by the outer end portions of said sections.

2. In a necktie pressing form of the class described, a substantially open V-shaped frame for insertion in a portion of the necktie comprising a pair of duplicate companion sections, each section being in the form of a longitudinally elongated channel-shaped member, intermediate filler blocks interposed between the flanges of the central portion of said members, said members being formed beyond the ends of said filler blocks with internal telescopically connected complementary ears, the ears at the respective ends of the frame being slotted, and connecting pins passing through said slots for joining the respective pairs of ears together, and a pair of independently operable arcuate springs arranged between said members and having their free end portions fitted in the channels of the members, the crown portion of the spring bearing against the respective and adjacent connecting pins.
3. In a necktie pressing form of the class described, a substantially open V-shaped frame for insertion in a portion of the necktie comprising a pair of duplicate companion sections, each section being in the form of a longitudinally elongated channel-shaped member, intermediate filler blocks interposed between the flanges of the central portion of said members, said members being formed beyond the ends of said filler blocks with internal telescopically connected complementary ears, the ears at the respective ends of said frame being slotted, and connecting pins passing through said slots for joining the respective pairs of ears together, and a pair of independently operable arcuate springs arranged between said members and having their free end portions fitted in the channels of the members, the crown portion of the spring bearing against the respective and adjacent connecting pins, the end portions of the filler blocks being notched to provide keeper seats and the terminal ends of the springs being engaged into the notches to aid in holding the springs in place.

In testimony whereof I affix my signature.
SAMUEL LOUIS GARFINKEL.
